SAUL OLINER
INVENTOR

BY *Walter E. Weilheim*
ATTORNEY

UNITED STATES PATENT OFFICE.

SAUL OLINER, OF SHANGHAI, CHINA.

HAIR NET.

Application filed September 25, 1924. Serial No. 739,850.

To all whom it may concern:

Be it known that I, SAUL OLINER, a citizen of the United States, and a resident of Shanghai, in the Province of Kiangsu and 5 the Republic of China, have invented certain new and useful Improvements in Hair Nets, of which the following is a specification.

This invention relates to improvements in 10 hair nets and the like, and has more particularly reference to the manner of weaving such nets, whereby their use as an article of the coiffure is rendered less noticeable, by reason of the means employed to 15 fashion them to the heads of their wearers.

The invention refers more specifically to the kind of net known in the trade as a cap net, and it is one of the particular objects to produce a net of this type which has a 20 substantially bag-like shape, by using a comparatively large size mesh structure of uniform size, surrounded at its open ends with a series of comparatively small size meshes of uniform size, to hold the net securely upon the coiffure. Another object 25 is to so knit together the large sized meshes, where they adjoin the small sized meshes that the desired bag-like shape is produced in a very novel manner.

30 To enable the means whereby I carry these improvements into effect to be readily understood, reference is made to the accompanying drawings in which—

Fig. 1 is a diagrammatic side view of the 35 hair net, showing a portion of the meshes only;

Fig. 2 is a fragmentary view drawn to a larger scale showing in detail the arrangement of its mesh structure; and

40 Fig. 3 is a diagrammatic view of a hair net, before the same is drawn together by the addition of the small sized meshes.

Like characters of reference denote similar parts throughout the drawings and the following specification.

45 10 is a hair net, designated ordinarily a self-adjusting cap net, composed of strands of hair 11. The major part of the hair net is made of net work of relatively large mesh

50 12. At the extreme end of the net, surrounding this large sized mesh, are several rows of relatively small sized net work 13, 13^a and 13^b which, when knitted on, draw the outer part of the net together to assume the shape 55 outlined in Fig. 1.

In knitting these nets which is done by

hand, a central oblong part 14, as shown diagrammatically in Fig. 3, is first made up of rows of large sized meshes. These rows are knitted in a crosswise direction. Surrounding this large sized net work 14, in the usual net as heretofore made, is then knitted small sized meshes at 14^b. This consists of usually two or more rows, having the same number of meshes as the adjoining large 60 sized rows. It is apparent that in such nets there is an excessive looseness at the rows of large sized mesh, immediately adjacent the rows of small sized mesh, giving the net a bulky appearance at this point and rendering it very noticeable.

In order to overcome these objectionable features, I knit several rows of large sized meshes around the central portion 14, indicated in the diagram in Fig. 3, as 14^a, before 75 I knit on the small sized meshes at 14^b. I reduce these rows 14^a which are composed of meshes of the same size as the central part 14, by one mesh at each of the four corners of the net where indicated by an X within 80 a circle in Fig. 3.

I accomplish this in the following manner clearly illustrated in Fig. 2 which shows a fragmentary view of one end of the oblong central netting composed of large sized 85 meshes, and which also shows several rows of the same size mesh surrounding it reduced in number of mesh in my novel manner, and several rows of small sized meshes at the outside of the net.

90 In detail, a, b, c and d are rows of large sized meshes near the central part of the net, made up of strands of hair 11 in the customary manner, in an oblong shape.

95 Knitted around this net work composed of large sized meshes is the lower half of row e which has a loop 15 near one of the corners of the oblong portion, instead of being connected to the next mesh, led back to its starting point 16. Upon inspection of Fig. 2, it will be seen that by doing so, the next row f is reduced at this point by one mesh. The same method is also followed in row f. Loop 17 is led back to its starting point 18 which also reduces row g by one 100 mesh at this point.

105 It is obvious that by eliminating two meshes in this manner, at each side of the oblong shaped net, or a total of four in each row when folded over to make the bag-shaped cap net, a reduction is made in the shape of the net, with respect to its center, at the same time 110

adhering to the little noticeable large sized meshes.

Rows *h*, *j* and *k* of small sized meshes are then knitted on all around the net, which draws the same together still further, and when folded along the plane of a median line lengthwise through the oblong of the net, causes it to assume the shape common to cap nets.

19 It is obvious that by making the reduction in meshes in rows *g* and *f*, the fullness of the net, immediately above the small sized meshes, is eliminated and at the same time the large sized mesh is maintained, except 15 at the four points of reduction, and its invisibility, as well as its self conforming qualities to the coiffure are greatly increased.

It is understood that various changes in the form, proportion and minor details of 20 the net may be resorted to without departing from the principle or sacrificing any of the advantages of the invention, as defined in the appended claims.

What I claim as new, is:

25 1. In a hair net, having a central oblong portion of rows of relatively large sized meshes, a plurality of rows of meshes, of the same size as the said central portion and knitted around it, having meshes dropped at 30 selected and symmetrically spaced positions in each row and in proximity to each other with respect to adjoining rows, and a number of rows of relatively small sized meshes immediately surrounding the plurality of 35 rows of large sized meshes around the said central portion.

2. In a hair net, consisting of a central

portion of large sized meshes and an outer portion of small sized meshes surrounding it, an intermediate portion of meshes of the same size as in the said central portion, interposed between the said central and outer portions, having a reduction in meshes at four symmetrically spaced points in rows of more than one and in adjacently staggered 45 relation to each other.

3. In a hair net having a central oblong part of large sized meshes, an outer portion consisting of a plurality of rows of small sized meshes, and an intermediate portion 50 surrounding the said central part and interposed between it and the said outer portion, consisting of a plurality of rows of mesh of the same size as in the said central part and having a reduction of mesh near 55 each of the four corners of the said oblong central part, the reduction in mesh of one row being adjacent to that in the adjoining row.

4. A hair net having an oblong major part 60 of large sized meshes surrounded by a plurality of rows of small sized meshes, the said major part having in the rows of meshes, immediately adjacent the said rows of small sized meshes, dropped meshes at selected positions in adjacently staggered relation to each other.

In testimony whereof I have hereunto set my hand and seal in presence of two subscribing witnesses.

SAUL OLINER. [L.S.]
